UNITED STATES PATENT OFFICE.

SLAUGHTER W. HUFF, OF BROOKLYN, NEW YORK.

INDICATOR FOR CARTRIDGE-FUSES.

1,301,848.

Specification of Letters Patent. Patented Apr. 29, 1919.

Application filed August 21, 1914. Serial No. 857,903.

To all whom it may concern:

Be it known that I, SLAUGHTER W. HUFF, a citizen of the United States, residing in the borough of Brooklyn, in the city and 5 State of New York, have invented certain new and useful Improvements in Indicators for Cartridge-Fuses, of which the following is a specification.

This invention relates to electric fuses to 10 be introduced into an electric circuit for limiting the current that can be fed to instruments and thus protect them from an overload; and particularly to so-called cartridge fuses where the fusible link is incased 15 and embedded, so that it becomes necessary to provide an indicator to show when the fuse has been blown. Various expedients have been suggested, such as the provision of a subsidiary conductor within the case 20 and in conductive relation to the fuse terminals, so that it is destroyed whenever the main fuse link is blown; this subsidiary conductor being rendered visible either through a reduced opening in the case, or 25 by bringing a portion of its length on the surface of the case; or its fusing being rendered manifest by causing it to discolor a chemically prepared label, either directly by 30 its own heat or through the medium of a slowly combustible substance; or in some instances by causing the gases of its fusion to disrupt a covering piece applied to the case. But these methods are uncertain and 35 unsatisfactory, because not positive enough in their effects, or because of the objection to having a portion of the subsidiary wire exposed. According to the present invention, the subsidiary wire is retained wholly 40 within the case, and a diminutive gun is formed in the wall of the case in such relation to said wire as to be discharged by the fusing of the wire; a breech closure in the form of a piece of fiber or other suitable material being provided on the inner wall of 45 the casing and as a means for holding the subsidiary wire in place, while a charge of (preferably) smokeless powder is introduced in the bore formed in the case and confined by a wad of plastic material, such 50 as plaster of Paris, which is readily displaced and the absence of which becomes the telltale or indicator when the fuse is blown.

The invention will be fully understood 55 upon reference to the illustrative embodi-

ment disclosed in the accompanying drawing, in which—

Figures 1 and 2 are axial longitudinal sections of a fuse embodying the present invention, showing, respectively, the condition 60 before blowing and the condition after blowing.

Fig. 3 is an end view of the fuse.

1 represents a tubular casing preferably of fiber, 2 the main fuse link embedded and 65 incased therein, 3 the end caps by which the ends of the casing are closed and through which electrical connection is made with the conductors within; said end caps being secured in place by any suitable means, such for 70 instance as the pins 3^a; and 4 the subsidiary or indicator wire which is laid along the inner wall of the casing and has its ends laid over the ends of the casing as at 4^a in position to remain in electrical contact with the 75 end caps 3.

According to the operative theory of the present invention, a means is provided of definite form and location which is adapted by its presence to indicate the fact that the 80 fuse remains intact and by its absence the fact that the fuse has been blown. This means consists of a wad 8 fitting a bore 5 in the wall of the casing and preferably made of some plastic material which can be conveniently and cheaply molded in place, and in order that it may be displaced by conditions indicating an overload of the fuse and impairment of its main conducting link, the bore carries beneath the wad 8, a charge 6 85 of explosive, preferably smokeless powder. In order to ignite this powder, either by a sudden fusing of the subsidiary wire or by a gradual heating up to the fusing point, the wire 4 is laid diametrically across the inner 90 end of the bore 5 and the bore is backed up and the wire held in place by a breech closure 7 underlying the inner surface of the casing and comprising a strip sufficiently substantial to cause the outward discharge 95 of the powder when ignited, particularly when the breech closure is backed up by the refractory filling of the fuse. The purpose of using a displaceable wad in a well defined bore instead of the various expedients 100 which have heretofore been proposed, such as mutilation of a label, discoloration of a target, or development of chemical changes by the heat or gases of fusion, is to develop 105 a physically well defined opening which can 110

be distinguished not only by the eye when the fuse is plainly visible, but by the sense of touch where the location of the fuse does not present it plainly to view. By comparing 5 Fig. 1 with Fig. 2, it will readily be seen that Fig. 1 presents a condition which to the eye will readily indicate that the fuse has not been impaired, particularly if the plastic material forming the wad 8 is 10 plaster of Paris or some other substance readily contrasting with the color of the casing, and it will indicate this condition readily to the sense of touch because of the comparative evenness of the surface when 15 the wad is in place, but when the bore 5 is entirely empty, as shown in Fig. 2, the condition is appreciated with equal readiness both to the eye and the touch.

The plaster of Paris or equivalent material 20 is advantageous for the further reason that it provides a substantially impervious closure for the bore which, on the one hand confines the gases of the propelling charge until sufficient to drive the projectile furnished by 25 the wad, and on the other hand protects the comparatively light explosive charge from dampness or other deteriorating influences. A still further advantage of a plastic closure for the bore is the cheapness in cost of labor 30 and material with which it can be supplied, it merely being necessary to wipe the ma-

terial in plastic state across the mouth of the bore to insure insertion and accurate fitting.

The breech closure 7 will be secured in position by any suitable means, as for instance 35 furnace cement. This means of securing the breech closure not only positions the strip until the filler can be packed into the casing, but it effectively seals the breech end of the bore around the wires, as well as between the 40 opposed faces of the strip and the casing.

I claim:—

In an indicator fuse having two end caps, an inclosing case having an opening in the wall thereof, a breech closure for the inner 45 end of said opening, a charge of explosive substance in the opening near the inner end thereof and adjacent to the breech closure, a seal consisting of plastic material filled in through the outer end of said opening and 50 resting directly upon the explosive substance, and igniting means comprising a conductor connected to the two end caps of the fuse and extending past and in contact with said explosive substance.

The foregoing specification signed at Brooklyn, N. Y., this 31st day of July, 1914.

SLAUGHTER W. HUFF.
